UNITED STATES PATENT OFFICE.

CHARLES A. RIVARD, OF PROVIDENCE, RHODE ISLAND, ASSIGNOR TO GORHAM MANUFACTURING COMPANY, OF PROVIDENCE, RHODE ISLAND, A CORPORATION OF RHODE ISLAND.

ENGRAVING-MACHINE.

1,281,838.

Specification of Letters Patent. Patented Oct. 15, 1918.

Application filed September 6, 1917. Serial No. 190,028.

To all whom it may concern:

Be it known that I, CHARLES A. RIVARD, a citizen of the United States, residing at Providence, in the county of Providence and State of Rhode Island, have invented 5 a new and useful Improvement in Engraving-Machines, of which the following is a specification.

This invention relates to certain new and 10 useful improvements in an engraving machine, and it has for its primary aim and object to provide a machine by which may be produced a roll for rolling metal wire that is much used for ornamental purposes.

15 A machine of this character by which such rolls may be produced has been a long felt want in the manufacturing trade, and it is, therefore, another object to provide a mechanism of a practical nature which will 20 be efficient in the production and formation of rolls for the rolling of metal wire.

Further, the invention resides in the features of construction and arrangements and 25 combinations of parts hereinafter described in detail and claimed in a succinct manner, reference being had to the accompanying drawings wherein

Figure 1 is a top plan view of an engraving machine embodying the present invention.

Fig. 2 is a front elevation thereof, portions being broken away, and

Fig. 3 is a transverse section through the machine on line 3—3 of Fig. 2.

35 Referring more particularly to the drawings, the numeral 1 designates the bed or body of the machine provided with spaced pairs of bearings 2 in which are journaled the shafts 3 and 4, the pattern shaft 3 being extended to carry a drive gear 5 which derives its source of power from any well known and desired form of transmission, such as at 6. The work operating shaft 4 carries a fixed gear 7 adapted to mesh with

40 either of two beveled gears 8 that are slideable on a third shaft 9, the latter having a driving connection with the shaft 3 through the intermediary of beveled gearing 10. Thus, a positive drive is obtained for each 45 of the parallel shafts 3 and 4, the ratio be-

tween the connecting gears being such as to give the shafts similar rotary movement.

The beam 11, is pivotally mounted at one end on a fulcrum plate 12 for relative horizontal movement, vertical movement being 55 permitted through the shaft 13 which carries the plate and is journaled in bearings 14 on the frame or bed 1. Vertical adjustment is accorded the beam by the adjustably mounted bracket arm 15 that extends outwardly from the bed beneath the beam, the latter having a roller bearing 16 running over the arm. A raising and lowering screw 17 is provided for adjusting the relative 60 height of the arm and beam.

65 The foregoing construction is that of the well known French engraving machine which is described and illustrated in the French patent to V. Janvier, No. 320,564, and which further includes a tracer 18, opposite the pattern shaft 3, and the milling cutter 19, opposite the work shaft 4, both being carried on the beam, as is clearly illustrated. The milling cutter is rotated by 70 means of an endless belt 20 passing about 75 the pulley 21, on the cutter shaft, and the several idlers 22, a suitable take-up 23 being provided at the pivot end of the beam.

In the French patent above referred to, a face plate was mounted on the outer or 80 front end of each shaft 3 and 4, one plate carrying the pattern and the other bearing the die blank to be cut.

A beveled gear 24 is substituted for each 85 face plate and with each gear 24 is intermeshed a horizontally disposed and downwardly facing gear 25, the same being fixed on the lower end of a vertical shaft 26 which is journaled in the overhanging bearing 27 of a bracket 28. This bracket has spaced 90 supporting webs which seat on the bearings 2 of the respective pair and are secured thereto by the screw bolts 29.

A bracket 30 is secured to the front of the bed under each overhanging bracket 28, as 95 by screw bolts 31, and through each bracket 30 is passed upwardly a centering pin 32 for supporting the master roll 33, carrying the pattern 34, and the roll 35 which is to be cut or engraved. The work roll 35 and 100

the master roll 33 are secured to the respective gear 25 by means of a clamp 36 which is pivoted to the under face of said gear for swinging to a convenient position.

5 In operation, the tracer in its movement over the pattern imparts an in and out motion to the beam which accordingly controls the cut of the milling cutter on the work roll and produces the pattern either in a reduced form, an enlarged form, or equal in size to the pattern.

From the foregoing, it will appear that the machine is capable of supplying a long felt want in the production of rolls which 15 are employed in the rolling of metal into ornamental material. The change in construction from the above referred to machine is comparatively slight and, with the additions mentioned such reconstruction 20 may be economically effected.

Having thus described my invention, what I claim as new and desire to secure by Letters Patent is—

1. In an engraving machine, a frame, 25 spaced pairs of bearings thereon, parallel shafts journaled in the bearings, means operatively connecting the shafts, a rotatable fulcrum plate on the frame, a beam arranged in front of the frame across the ends of the 30 shafts and pivoted to the plate for in and out movement, a beveled gear on the forward end of each shaft, a bracket secured on the bearings of each pair and having an overhanging shaft bearing vertically disposed, a shaft in each bracket, a beveled gear on the lower end of each last named shaft meshing with the first beveled gear, a work-holding clamp pivoted eccentrically on the under face of each second beveled gear, a 40 bracket secured to the front of the frame and underlying a respective first named bracket, a centering pin vertically disposed in each underlying bracket to coöperate with the respective work clamp for holding 45 vertically disposed pattern and die rolls, a tracer carried on the beam opposite the pattern roll, and a milling cutter journaled on the beam opposite the die roll.

2. In an engraving machine, a frame, a 50 pair of shafts journaled thereon, a beveled gear fixed on each shaft, a bracket overhanging each gear and provided with a vertically disposed shaft bearing, a vertical shaft in each bracket bearing, a beveled 55 gear carried on the lower end of each vertical shaft, said second gear operatively connected with the first gear, a bracket underlying each second gear, a centering pin passed upwardly through each second 60 bracket, means carried by each second gear and coöoperating with the respective underlying pin for holding the pattern and die rolls, a beam mounted for in and out motion adjacent the rolls, a tracer carried by the

beam for operating on the pattern roll, a 65 milling cutter journaled on the beam for operating on the die roll, and means for rotating the cutter.

3. In an engraving machine, horizontally disposed pattern and work operating shafts, 70 a pair of vertically disposed shafts connected therewith, a centering pin arranged beneath each vertical shaft, a pattern roll vertically supported by one pin and its overlying vertical shaft, a work roll likewise supported 75 by the other pin and its overlying shaft, a tracer for operating on the pattern roll, a cutter for operating on the work roll, and a beam support for the tracer and cutter, mounted for in and out motion and vertical 80 adjustment.

4. In an engraving machine for producing rolls for rolling metal wire, means for engaging the opposite ends of pattern and work rolls for rotation about vertical axes, 85 means for rotating the rolls, a tracer for the pattern roll, a cutter for the work roll, and a beam supporting the tracer and cutter for in and out motion.

5. In an engraving machine, a frame, a 90 pair of shafts journaled thereon, a beveled gear fixed on each shaft to be rotated thereby, a bracket overhanging each gear and provided with a vertically disposed shaft bearing, a vertical shaft in each bracket 95 bearing, a beveled gear carried on the lower end of each vertical shaft, said second gear operatively connected with the first gear, means coöoperating with the second gears for supporting the pattern and work, a beam mounted for in and out motion relative to the pattern and work, a tracer carried by the beam for operating on the pattern, and a cutter also carried by the beam for action on the work.

6. In an engraving machine, a beam mounted for in and out motion, a tracer and cutter carried thereby, and means for rotatably supporting the pattern element and work element adjacent the tracer and cutter 110 respectively, one of said elements being a roll engaged at its opposite ends for rotation about its vertical axis.

7. In an engraving machine, a pair of parallel related horizontal shafts, means for 115 rotating the same, vertical shafts geared to the horizontal shafts, means carried by each vertical shaft for securing a vertical roll axially thereto, a cutter for operating on one roll, a tracer for coöoperating with the other roll, and means supporting the tracer and cutter for movement.

8. In an engraving machine, a pair of gears operatively connected, a clamp pivoted on a face of each to swing toward and 125 away therefrom, a pattern roll secured to one gear by the adjacent clamp engaging one end thereof, a vertical work roll engaged

by the other clamp for securing one end thereof to the other gear, and means engaging the opposite ends of the rolls for holding the rolls axially related with the gears and the clamps substantially against the faces of the latter.

5 In testimony whereof I have signed my

name to this specification in the presence of two subscribing witnesses.

CHARLES A. RIVARD.
